UNITED STATES PATENT OFFICE

131,145

DESIGN FOR AN ENVELOPE OR SIMILAR ARTICLE

Theodore Edson Jewell, Jr., Newton, Mass.

Application April 1, 1941, Serial No. 100,074

Term of patent 14 years

To all whom it may concern:

Be it known that I, Theodore Edson Jewell, Jr., a citizen of the United States and a resident of Newton, county of Middlesex, and State of Massachusetts have invented a new, original, and ornamental Design for an Envelope or Similar Article, of which the following is a specification, reference being made to the accompanying drawing forming part thereof.

In the drawing showing my new design, the figure is a plan view of an envelope showing my new design.

The side of the envelope not shown is sub-

stantially the same as the side shown in the drawing figure.

The characteristic features of the design reside in the specific alternately arranged large and small diamond-shaped figures connected to each other in a horizontal direction to form rows, with adjacent rows spaced from each other in a vertical direction, all as shown in the drawing.

I claim:

The ornamental design for an envelope or similar article, as shown and described.

T. EDSON JEWELL, JR.
